UNITED STATES PATENT OFFICE.

ROBERT COOPER, OF SCRANTON, PENNSYLVANIA, ASSIGNOR TO THE HUDSON COAL COMPANY, OF SCRANTON, PENNSYLVANIA.

MATERIAL-HANDLING MEANS.

Application filed January 23, 1928. Serial No. 248,766.

The invention relates primarily to traveling belts and chutes leading thereto for supplying coal to said belts. As long as the coal slides down a chute onto the subjacent belt, 5 in comparatively small quantity, it is guided substantially uniformly onto said belt by a pair of wing boards which project from the lower end of the chute over the longitudinal edge portions of the belt, but when a large 10 quantity of coal rushes down the chute, for instance, when discharged into the latter from a rotary car dump, the belt is not uniformly loaded but at that time receives an excess of coal. Hence, the strain upon the 15 belt is excessive at times to its severe detriment.

It is the object of my invention to provide the above-named wing boards with deflectors spaced outwardly from the discharge end of 20 the chute, toward the delivery end of the belt, so that coal in small quantity may discharge from said chute onto said belt without necessarily coming in contact with said deflectors. Upon rush of a large quantity 25 of coal down the chute, however, the coal is checked by these deflectors and is gradually and uniformly distributed along the belt, so that the latter is relieved of excessive strain.

It is another object of the invention to 30 form the deflectors of resilient nature to avoid breakage of large lumps of coal, due to the fact that these deflectors will yield outwardly under pressure. Furthermore, their ability to yield in this manner prevents jamming of the aperture between them, by large 35 lumps which could not pass through such aperture without this yieldable characteristic of the deflectors.

With the foregoing in view, the invention 40 resides in the novel subject matter herein-after described and claimed, description being accomplished by reference to the accompanying drawing.

Fig. 1 is a top plan view of a material 45 handling apparatus improved in accordance with my invention.

Fig. 2 is a longitudinal sectional view on the correspondingly numbered line of Fig. 1.

The drawing above briefly described, illus- 50 trates the preferred form of construction and while this construction will be herein explained, it is to be understood that within the scope of the invention as claimed, variations may be made.

The numeral 3 denotes a belt which travels 55 in the direction of the arrow in Fig. 2, and 4 has reference to a chute which declines to said belt. Continuous with the side walls 5 of the chute 4, are laterally spaced wing boards 6 whose outer ends 7 are usually decreased in height. The lower and upper 60 edges of the wing boards 6 are stiffened by angle metal bars 8—9 respectively, which also extend along the upper and lower portions of the chute 4, the horizontal flanges 65 of the bars 8 extending inwardly under the lower edges of the wing boards 6, whereas the horizontal flanges of the bars 9, project outwardly from the upper edges of said wing boards. 70

The wing boards 6 project outwardly beyond the lower end of the bottom 10 of the chute 4 and are provided with inwardly projecting deflector plates 11 spaced outwardly from said lower end of the bottom 10, toward the delivery end of the belt 3. The vertical edge portions of the plates 11, toward the chute 4, are secured against the inner sides of the wing boards 6 by rivets or the like 12 and from these secured 75 edges, the plates converge toward the aforesaid delivery end of the belt 3, the free edges of said plates being curved outwardly at 13. Spring steel is preferably used in constructing the plates 11, permitting them to yield 80 outwardly, although other provision could be made for attaining this end. 85

As long as coal in small quantity is sliding down the chute 4, it is received upon the belt 3, in the space between the deflectors 11 and the chute bottom 10. When a large quantity 90 of coal rushes down said chute, for instance from a rotary car dump, this quantity of coal is arrested in its discharge movement, by the deflector plates 11 and is permitted 95 to travel on with the belt, only in predetermined quantity, uniformly distributed along said belt, so that the latter cannot be overloaded at one point or another. Any large lumps of coal striking the plates 11 100 will not be broken by them, in view of the fact that they may outwardly yield. Moreover, any lumps too large to pass between said plates, will merely cause outward yielding of them, permitting passage, instead of 105 clogging the aperture between the ends 13. Excellent results are obtainable from the general construction shown and it may there-

fore be followed if desired. However, as above stated, variations may be made within the scope of the invention as claimed.

I claim:—

- 5 1. In a heavy-material handling means having a traveling belt, a chute declining to said belt, and laterally spaced wing boards projecting beyond the lower end of the chute bottom toward the discharge end of the belt; material-distributing deflectors carried by said wing boards and projecting inwardly therefrom, said deflectors being adjacent to but spaced toward said discharge end of the belt from said lower end of the chute bottom, 10 whereby to permit material sliding down said chute in small quantity to discharge onto said belt and pass between the deflectors without necessarily striking the latter, but to arrest any rush of material in large quantity
- 15

and allow that checked between said deflectors and the chute bottom to rest on the belt to be gradually carried off by the latter.

2. A structure as specified in claim 1; said deflectors converging toward the delivery end of said belt.

25 3. A structure as specified in claim 1; each of said deflectors consisting of a vertically disposed plate secured at one edge to the adjacent wing board and having its opposed vertical edge directed outwardly, the two plates converging toward the delivery end of said belt.

30 4. A structure as specified in claim 1; said deflectors being outwardly yieldable.

35 In testimony whereof I have hereunto affixed my signature.

ROBERT COOPER.
